UNITED STATES PATENT OFFICE.

MARSHALL BURNS LLOYD, OF MENOMINEE, MICHIGAN, ASSIGNOR, BY MESNE ASSIGNMENTS, TO THE ELYRIA IRON & STEEL COMPANY, OF ELYRIA, OHIO, A CORPORATION OF OHIO.

MACHINE FOR REDUCING AND SURFACE-FINISHING METAL TUBES, RODS, AND THE LIKE.

1,184,972.

Specification of Letters Patent.

Patented May 30, 1916.

Original application filed August 7, 1912, Serial No. 713,851. Divided and this application filed September 19, 1913. Serial No. 790,776.

To all whom it may concern:

Be it known that I, MARSHALL B. LLOYD, a citizen of the United States, and resident of Menominee, in the county of Menominee and State of Michigan, have invented certain new and useful Improvements in Machines for Reducing and Surface-Finishing Metal Tubes, Rods, and the like, of which the following is a specification.

10 My invention relates generally to improvements in mechanisms for reducing metal tubing to specified circular cross section and for finely polishing or surface finishing the same.

15 This application is a division of my pending application Serial No. 713,851, filed August 7th, 1912, and directed to the process which is incidentally described herein.

20 The general object of my invention is to provide a mechanism by which it shall be possible to reduce metal tubing to specified size and to polish the same more rapidly and at less cost than can be done with known mechanisms.

25 Where the terms "tube" and "tubing" are used in this specification and in the appended claims, they are to be read as meaning metal tubing generally, though relating more particularly to thin walled tubing.

30 My invention resides in a machine of the construction and combination of parts hereinafter described, and adapted to hold the tubing positively against rotation while feeding it forward at constant speed and 35 also adapted to subject the surface of the tubing to the high speed but reluctant rotative action of a large number of small approximately parallel cross rolls, whereby the tubing is gradually reduced to a circular 40 form and provided with an outer skin having a circumferential trend and which is highly polished.

The invention will be more readily understood by reference to the accompanying 45 drawings, forming part of this specification, and in which:—

Figure 1 is a plan view of a machine embodying my invention. Fig. 2 is a side elevation thereof. Fig. 3 is a longitudinal vertical section, considerably enlarged, on the line X—X of Fig. 1. Fig. 4 is a further enlarged cross section on the line Y—Y of

Fig. 3. Fig. 5 is an end view of one of the roller rings and a number of rolls, which completely fill same. Fig. 6 is a longitudinal section thereof. Fig. 7 is a view similar to Fig. 5 but showing rolls which do not completely fill the annular space between the tube and the ring. Fig. 8 is a longitudinal section thereof showing the action of such rolls when in operation. Fig. 9 is a side view of one of the rolls; and Fig. 10 depicts a roll of modified form.

The mechanism shown herein may be used in the continuous tube mill that is described and claimed in Letters Patent No. 1,027,865, granted May 28th, 1912, in which case the continuous or traveling vise herein marked A will replace the traveling vise marked E in that patent. On the other hand the herein shown mechanism may be used for reducing and finishing successive and relatively short pieces of tubing.

One important step of my said process consists in holding the tube to be reduced, against rotation while it is advancing. I do not attempt to treat the whole length and surface of the tubing at one time but restrict the reducing and finishing forces to one locality and by feeding the tube forward to and through that locality the said forces progressively reduce the tubing and finish its surface. To thus hold the tubing against rotation and at the same time positively advance or feed it forward at a constant rate of speed, I employ the traveling or continuous vise A, and preferably also employ a second traveling vise B, which may be of less length and relatively of less strength. These traveling vises are fixed upon a bench or table Z, and are driven by a train of gearing C, means being interposed to compensate for the elongation of the tubing between the two vises, due to the reduction of the tubing by the reducing and polishing mechanism. Primarily each vise comprises an endless conveyer equipped with a plurality of pairs of laterally opening and closing jaws A'. In the working stretches of the vises the jaws A', are closed together upon the tube. As the jaws grasp the tube in this manner and as the jaw carrying conveyers are in constant rotation, it is obvious that

100 the tube will be propelled forward at a sub-

stantially constant rate of speed. The detail construction of the vises is not of material moment in this case, and is clearly described in aforesaid patent. It may be explained that the jaws of the vises are provided with grooves α , which fit the tube and when opposing pairs of jaws are closed in the working stretch of the device they substantially inclose the portion of tubing 10 which they engage and an effective gripping of the tubing by the vise is thus insured. It may also be explained that the working stretches, and the jaw grooves thereof, belonging to the two vises A and B are arranged in alinement so that the traveling vises have no tendency to bend or twist the tubing.

It will be noted that the space between the two vises is occupied by another mechanism or tool, D, which is also attached to the table or bench Z. This tool is the rolling appliance referred to, which I employ for reducing and finishing the tubing, in the interval of its passage from the vise A to 25 the vise B. Throughout the drawings, the tubing is indicated by the letter T. The direction of travel of the tubing is indicated by arrows in Figs. 1, 2 and 3.

I perform the surface rolling operation at 30 high speed, accomplishing same by a plurality of annular series of small rolls which are confined circumferentially and with relation to the tubing. These series I rotate rapidly, and each small roll thereof rolls 35 upon the surface of the tubing at high speed and turns bodily around the tubing many times per minute. The first series of rolls, or the first several series of rolls, force the tubing fed thereto to a round shape and 40 may somewhat reduce its size. The next series of rolls is confined within a smaller circumference than the first and the tube in its passage is reduced in diameter to the extent of the difference between the internal 45 circumference of the first annular series and that of the second annular series of rolls. I sometimes employ still other series 50 of rolls of gradually diminishing internal or working circumferences, and by such means gradually roll down or reduce the tubing to specified diameter and circumference. While thus reducing the size of the tubing to the extent determined by the pre- 55 arrangement of the reducing rolls, those rolls at the same time gradually smooth the surface of the tubing and form thereon a surface skin, the grain or trend of which is circumferential, as opposed to the longitudinal grain of the body of the tubing. To 60 perfect the surface I prefer to add one or more series of rolls distinguished by internal working circumferences substantially identical with that of the last series of reducing and surfacing rolls.

65 While I have mentioned the tubing as be-

ing held against rotation and such holding as being an important part of my said process, it should be understood that the term "holding the tubing against rotation", or the like, is relative or comparative, meaning 70 that it must not be permitted to rotate at the speed at which the reducing rolls rotate.

The high speed rolling mechanism D, appearing in Figs. 1 and 2, will be best understood upon reference to Figs. 3 to 10. 75 The parts 2 are bearing blocks containing bearings 3 and secured upon a bed plate Z' on the table Z. The bearings 3, are in exact alinement and contain two sleeves 4 and 5. Each sleeve contains a central hole 6, 6' to 80 receive the tubing. In addition to the central opening, the sleeves contain larger chambers 4' and 5' closed at the discharge ends by screw plugs 4'', 5'', respectively. The plugs contain central openings for the tubing. The chambers 4' and 5' are concentric with the axis of the tubing. The sleeves 4 and 5 are likewise concentric with the axis of the tubing. Within each chamber 4 and 5 I provide a plurality of hardened steel 90 races or rings R which are, internally, cylindrical. The rings are made to fit snugly within respective sleeves, and keys, 4^a and 5^a, hold them against rotation in respective sleeves. The parts marked S are small cylindrical rolls, before referred to. These are shorter than the rings which contain them to insure a proper race bearing. For clearness of illustration, all of these rolls in Fig. 3 are shown as of the same diameter. It will 100 be noted that the rolls are held against longitudinal movement by internal abutments or flanges R', provided on the rings R for the purpose. The diameter of the tubing as it approaches the mechanism D is greater than 105 the diameter of the tubing as it is discharged from that mechanism.

The internal or working diameter of the series of small rolls in the ring R, at the receiving end of the mechanism D, is greater 110 than that of any other series in the mechanism. The internal or working circumference of the series of rolls held in this first ring may be no greater than the circumference of the tube T at that point, or may be 115 slightly less if desired. The next ring R, is slightly smaller in working circumference; and such reduction of diameter proceeds from ring to ring, preferably until the last rings, including the wide ring R'', are 120 reached in the sleeve 5. The diminishing sizes of the rings are indicated by the dotted lines of Fig. 3, distinguished by the dimension marks W and V.

The rolls in each ring may bear that relation to the ring and the tube which is depicted in Figs. 5 and 6, or their relation may be as depicted in Figs. 7 and 8. In the case of Figs. 5 and 6, the rolls S may bear one against the other and snugly fill the ring 130

R. Such rolls maintain positions substantially parallel with the axis of the tubing, when the containing ring R is rotated about the same. In the case of Figs. 7 and 8 the rolls are relatively smaller or fewer and they do not completely fill the containing ring. In consequence, spaces are left between the rollers, as shown in Fig. 7. In both cases, the tubing, obviously, completely fills the opening within (or internal circumference of) the series of rolls, and the external circumference of the tube T, depicted in Figs. 5 and 7, is fixed by the internal or working circumference of the series of rolls.

15 A difference of degree in action, between the arrangement of Fig. 5 and the arrangement of Fig. 7 is occasioned by the looseness of the rolls S, in the ring of Fig. 7; for as indicated in Fig. 8, the rotation of the containing ring R causes one end of each roll to lag behind its other end, so that the rolls assume oblique positions in the containing ring. In other words, each roll that is allowed such latitude of movement within 20 the ring, will bear upon the containing ring at its ends and will lie in a plane which intersects the axis of the tubing.

25 The parallel rolls of Figs. 5 and 6 serve to condense the metal of the tube and thereby reduce its diameter, and also serve to roll down and polish the tube's surface. The rolls of Figs. 7 and 8 perform the same functions but in addition they operate more effectively as cross rolls and tend to propel the 30 tube longitudinally.

35 The sleeves 4 and 5 are equipped with respective pulleys or drivers 7 and 8. Thrust bearings 9, arranged between the ends of the pulleys and the adjacent bearing blocks 2, prevent endwise movement of the sleeves 4 and 5 in their bearings. These pulleys 7 and 8 may be driven by belts 7' and 8'.

40 The rotation of the closely contacting rolls S has a tendency to twist the tubing T, and when necessary to counteract this tendency, I prefer to drive the roll containing sleeves 4 and 5 in opposite directions, as indicated by the crossed belts shown in Fig. 2. I admit water under pressure to the roll 45 containing sleeves, as by a supply pipe 11. The water flows in opposite directions within the two sleeves and among the rolls, finding escape at the end of the sleeves. In passing between the tube and the rolls, the 50 water sufficiently lubricates the latter and cleanses both the rolls and the surface of the tubing, while keeping the temperature of the surface of the tubing at such a low point as to insure a smooth bright finish. When a 55 very high finish is desired I sometimes use soapy water as a lubricant.

60 It will be understood that the cylindrical rolling surface of each roll S is a hardened and preferably ground surface. It will also be understood that the inner cylindrical sur-

faces of the several rings are likewise hardened and ground. The smoothness of these parts is transmitted or communicated to the surface of the tubes. The rolling action is so rapid that the tubing may be fed through 70 the mechanism at the rate of several feet per minute.

75 I prefer that the rolls in the receiving end of the mechanism shall be of the form and arrangement shown in Figs. 7 and 8. When so arranged the rapidly rotating rolls exert a very considerable pulling force upon the non-rotating tubing T. This force may be utilized as the only force for feeding the tubing, in cases where adequate means are 80 provided for preventing the rotation of the tubing. However, the special advantage of the Figs. 7 and 8 arrangement lies in the cross rolling effect of rolls arranged at slightly oblique angles to the tubing, which 85 facilitates the reduction of the tubing.

90 Where I rely upon the first series of small rolls to markedly reduce the diameter of the tubing, I prefer that the oppositely running rolls in the sleeve 5 shall be mostly of 95 the form and arrangement shown in Figs. 5 and 6 to the end that they may counteract the twisting effect of the reducing rolls and still avoid setting up a powerful re-action against the propelling effort of the rolls in 100 the sleeve 4.

105 The small rolls may have smooth surfaces, as shown in Fig. 9, or may contain spiral clearance grooves, as shown in Fig. 10. I find the smooth rolls to be better under most 110 circumstances.

115 It is evident that the reducing effect of each set of rolls is limited to a minute fraction of an inch, and that while the compression or reduction is chiefly dependent upon 120 the cross rolling of the rolls the polishing of the surface is in a measure due to the sweeping effect of the high speed rolls. It may be said of the surface of the metal that because of the high speed of attack, by the reluctantly rotating rolls, the surface metal of the tube is to a practical degree kept in a flowing or plastic state (this notwithstanding the application of cooling water) and from this fact it follows that in the surface skin of the 125 tube the longitudinal grain or trend of the metal is converted into a circumferential or transverse trend or grain, and this skin very readily submits to the cross rolling and sweeping action of the rolls, ultimating in the production of an extremely smooth, fine 130 finish or polish. It should be observed that the rolls are smaller than the tube, a great number thereof attacking its surface. Also the rolls are of greater length than diameter. 135

140 Attention is called to the position of the several sets of rolls. It will be noted that they are separated by spaces which are shorter than the small rolls. Such arrangement avoids freeing the metal between the 145

several series and prevents the spiraling or marking of the tube surface.

Thus far in my experience I have secured the best results by feeding the tubing at a speed of from three to five feet per minute, and by rotating the roll containing sleeve or sleeves at a speed of several thousand revolutions per minute.

I claim:—

- 10 1. The herein described machine comprising a rotary sleeve having a central tube opening and containing a plurality of internally cylindrical rings each in turn containing a series of cylindrical tube-rolling rolls.
- 15 2. The herein described machine comprising a plurality of concentric internally cylindrical rotary rings filled with a series of smaller cylindrical tube rolling rolls, means for rotating said rings, and suitable means 20 for holding a tube against rotation therewith.
- 25 3. The herein described machine for cold rolling tubing, comprising means for holding a tube against rotation, while leaving it free to move longitudinally, a plurality of concentric internally cylindrical rings, a series of smaller and shorter rolls therein, and means for rotating said rings.
- 30 4. The herein described tube finishing and polishing machine, comprising a rotary element containing a central opening formed by an annular series of longitudinally disposed cylindrical rolls, means circumferentially and longitudinally restraining said rolls in said element, means for rotating said element, and mechanism for holding the tube against rotation and advancing it through said element.
- 35 5. The herein described tube finishing and polishing machine, comprising a sleeve in combination with a plurality of series of cylindrical rolling rolls arranged therein to form a central recess, and means for rotating said sleeve.
- 40 6. The herein described tube finishing and polishing machine comprising, in combination, a sleeve mounted for rotation, a plurality of internally cylindrical rings centrally arranged therein and fixed to rotate therewith, and a plurality of longitudinally disposed rolls arranged in each ring and shorter than the same and defining a central opening through the sleeve.
- 45 7. The herein described tube finishing and polishing machine comprising in combination a sleeve, a number of annular series of cylindrical rolls arranged therein, means for rotating the sleeve, and means for holding a tube against rotation in said sleeve.
- 50 8. The herein described tube-finishing and polishing machine comprising in combination, a sleeve provided with a central opening and mounted for rotation, a plurality of internally cylindrical rings arranged within the sleeve, each ring encircling a plurality of

shorter rolling rolls, end abutments for said rolls, means for rotating the rings, and means for holding a tube against rotation when acted upon by said rolling rolls.

9. In a machine of the class described the combination of a sleeve mounted for rotation, a plurality of internally cylindrical rings arranged within the sleeve and fixed to rotate therewith, a plurality of cylindrical rolling rolls arranged within each ring, and means for holding a tube against rotation when subjected to the action of the rolling rolls. 70

10. In a device of the class described a sleeve containing a central opening, a plurality of internally cylindrical rings arranged therein each of said rings containing and guiding a plurality of cylindrical rolling rolls, which define a central opening of substantially the size of the tube to be treated, means for holding a tube against rotation, and means for forwarding a tube through said central opening. 80

11. In a device of the class described, the combination of a sleeve mounted for rotation, a plurality of internally cylindrical rings fixed within the sleeve to rotate therewith, a plurality of cylindrical rolling rolls arranged in each ring, means for holding a tube against rotation when acted upon by the rolling rolls, and means for forwarding a tube through the sleeve. 90

12. The herein described tube finishing and polishing machine comprising in combination a sleeve, a plurality of annular series of cylindrical rolls rotatably held therein and arranged to define a central opening, and means for holding the rolls against longitudinal movement. 100

13. The herein described tube-finishing machine comprising in combination a sleeve arranged for rotation, a plurality of internally cylindrical rings arranged therein, an annular series of cylindrical rolls arranged within each ring and shorter than the same, 110 abutments for said rolls, the rings and rolls together defining a central opening, and means for holding the rolls against longitudinal movement.

14. The herein described tube-finishing machine comprising in combination a sleeve arranged for rotation, a plurality of internally cylindrical rings arranged therein, an annular series of small rolls arranged within each ring, the rings and rolls together defining a central opening, means for holding the rolls against longitudinal movement, and means for forwarding a tube through the central opening. 115

15. The herein described tube-finishing machine comprising in combination a sleeve arranged for rotation, a plurality of internally cylindrical rings arranged therein, an annular series of cylindrical rolling rolls arranged within each ring, the rings and rolls 120

- together defining a central opening, means for holding the rolls against longitudinal movement, and means for holding a tube against rotation when acted upon by said rolling rolls.
16. The herein described tube-finishing machine comprising in combination a sleeve arranged for rotation, a plurality of internally cylindrical rings arranged therein, an annular series of cylindrical rolls within each ring, the rings and rolls together defining a central opening, means for holding the rolls against longitudinal movement, and means for forwarding a tube through the opening and for holding it against rotation while passing therethrough.
17. The herein described tube-finishing and polishing machine comprising a sleeve in combination with a plurality of annular series of cylindrical rolls, arranged for rotation therein, means for rotating the sleeve, and means for supplying a lubricating liquor to the rolls.
18. In a machine of the class described, the combination of a sleeve mounted for rotation, a plurality of internally cylindrical rings arranged therein and fixed to rotate therewith, an annular series of cylindrical rolling rolls arranged within each ring, means for rotating said rings, means for supplying a lubricating liquor to the rolls, and means for holding the rolls against longitudinal movement.
19. In a machine of the class described, the combination of a sleeve mounted for rotation, a plurality of internally cylindrical rings arranged therein and fixed to rotate therewith, an annular series of cylindrical rolling rolls arranged within each ring, means for rotating said rings, means for supplying a lubricating liquor to the rolls, means for holding the rolls against longitudinal movement, and means for forwarding a tube through the rings.
20. In a machine of the class described the combination of a sleeve mounted for rotation, a plurality of annular series of cylindrical rolling rolls arranged within the sleeve and defining a central opening, means for rotating the sleeve and bearings arranged to take the end thrust caused by the movement of the tube therethrough.
21. The herein described tube-finishing and polishing machine, comprising a sleeve arranged for rotation and constraining a plurality of cylindrical rolling rolls, means for rotating said sleeve, tube forwarding means, and end thrust bearings for said sleeve.
22. The herein described tube-finishing and polishing machine, comprising in combination a sleeve arranged for rotation and constraining a plurality of cylindrical rolling rolls, means for rotating said sleeve, tube forwarding means, and an end thrust
- bearing for said sleeve, and means for holding the tube against rotation when acted upon by said rolling rolls.
23. In a machine of the class described a sleeve containing a central opening, a plurality of internally cylindrical rings arranged therein, and an annular series of cylindrical rolls arranged within each ring, bearings for rotatably supporting said sleeve, other bearings arranged to take the end thrust thereof, and means for supplying a lubricating liquor to said rolls.
24. In a machine of the class described, a sleeve mounted for rotation, a plurality of annular series of similar length rolling rolls arranged therein, and a plurality of relatively elongated rolling rolls arranged therein, as and for the purpose specified.
25. The herein described tube finishing and polishing machine, comprising in combination a sleeve, a plurality of series of annular rolling rolls arranged within the sleeve, and formed to define a gradually diminishing central opening.
26. The herein described tube finishing and polishing machine, comprising in combination a sleeve, a plurality of series of annular rolling rolls arranged within the sleeve, and formed to define a gradually diminishing central opening, and a plurality of elongated rolls at the end of the reducing series and formed to define an opening of substantially the same size as the last annular series of rolls forming the diminishing opening.
27. The herein described tube finishing and polishing machine, comprising a sleeve mounted for rotation, in combination with a plurality of rings arranged within the sleeve and fixed to rotate therewith, an annular series of rolling rolls arranged within each of the rings and formed to define a diminishing central opening, and a single elongated ring arranged adjacent the last of the reducing rolls and containing an annular series of elongated rolling rolls defining an opening substantially the same size as that defined by the last of the reducing series.
28. The herein described tube finishing and polishing machine, comprising in combination, a sleeve mounted for rotation, a plurality of rings arranged within the sleeve and fixed to rotate therewith, an annular series of rolls arranged within each of the rings, and formed to define a diminishing central opening, a single elongated ring arranged adjacent the last of the reducing rolls and containing an annular series of elongated rolling rolls defining an opening substantially the same size as that defined by the last of the reducing series, and means for holding the tube against rotation while passing through said mechanism.
29. The herein described tube finishing

and polishing machine, comprising in combination a sleeve mounted for rotation, a plurality of rings arranged within the sleeve and fixed to rotate therewith, an annular series of rolling rolls, arranged within each of the rings and formed to define a diminishing central opening, a single elongated ring arranged adjacent the last of the reducing rolls and containing an annular series of elongated rolling rolls defining an opening substantially the same size as that defined by the last of the reducing series, means for forwarding the tube through said mechanism, and means for holding the tube against rotation therein.

30. The herein described tube finishing and polishing machine, comprising in combination a sleeve mounted for rotation, a plurality of rings arranged within the sleeve and fixed to rotate therewith, an annular series of rolls arranged within each of the rings and formed to define a diminishing central opening, a single elongated ring arranged adjacent the last of the reducing rolls and containing an annular series of elongated rolling rolls defining an opening substantially the same size as that defined by the last of the reducing series, and means for holding the said rolls against longitudinal and radial movement.

31. In a machine of the class described, the combination of two sleeves mounted for rotation, a plurality of annular series of cylindrical rolls arranged in each sleeve and positioned to define a central opening therethrough, and means for rotating said sleeves in opposite directions.

32. In a machine of the class described, the combination of two sleeves mounted for rotation, a plurality of annular series of cylindrical rolls arranged in each sleeve and positioned to define a central opening therethrough, means for rotating said sleeves, and means for forwarding a tube through said mechanism.

33. In a machine of the class described, the combination of two sleeves mounted for rotation, a plurality of annular series of cylindrical rolls arranged in each sleeve, and positioned to define a central opening therethrough, means for rotating said sleeves in opposite directions, and means for forwarding a tube through said mechanism and for holding it against rotation therein.

34. In a device of the class described, the combination of two sleeves mounted for rotation, a plurality of internally cylindrical race rings arranged within said sleeves and fixed to rotate therewith, an annular series of cylindrical rolls arranged to rotate within each ring, and means for imparting rotation to said sleeves and rings.

35. In a device of the class described, the combination of two sleeves mounted for rotation, a plurality of internally cylindrical

race rings arranged within said sleeves and fixed to rotate therewith, an annular series of cylindrical rolls arranged to rotate within each race ring, means for imparting rotation to said sleeves and rings, and a removable plug in each sleeve to permit the removal of said rings and rolls.

36. In a device of the class described, the combination of two sleeves mounted for rotation in opposite directions, a plurality of rings arranged within said sleeves and fixed to rotate therewith, an annular series of rolls arranged to rotate within each ring, means for imparting opposite rotation to respective sleeves and rings, and means for supplying a lubricating liquor to said rolls.

37. The herein described tube finishing and polishing machine, comprising in combination two sleeves mounted for rotation, a plurality of annular series of rolls arranged within the sleeves, and means for rotating the sleeves in the opposite directions, as and for the purpose specified.

38. The herein described tube-finishing and polishing machine, comprising in combination two sleeves mounted for rotation, a plurality of annular series of rolls arranged within the sleeves, means for rotating the sleeves in opposite directions, and means for forwarding a tube through said sleeves, as and for the purpose specified.

39. The herein described tube finishing and polishing machine, comprising in combination two sleeves mounted for rotation, a plurality of annular series of rolls arranged within the sleeves, means for rotating the sleeves in opposite directions, and means for holding the tube against rotation in its passage through said sleeves.

40. The herein described tube-finishing and polishing machine, comprising in combination two sleeves mounted for rotation, a plurality of annular series of rolls arranged within the sleeves, means for rotating the sleeves in opposite directions, means for forwarding a tube through said sleeve, and means for holding the rolls against longitudinal movement in said sleeves.

41. In a device of the class described, the combination of two sleeves mounted for rotation, a plurality of annular series of rolling cylindrical rolls arranged within said sleeves, means for rotating said sleeves, and thrust bearings to take the end thrust from each of said sleeves.

42. In a device of the class described, the combination of two longitudinally aligned sleeves, a plurality of similar length rolling rolls arranged in annular series within said sleeves, and a plurality of relatively long rolling rolls arranged in one of the sleeves as and for the purpose specified.

43. The herein described tube-finishing and polishing machine, comprising in combination two sleeves, a plurality of rings

arranged within the sleeves and fixed to rotate therewith, an annular series of rolls arranged within each of the rings, a number of the annular series of rolls being of similar length and a number thereof at one end of one of the sleeves being relatively elongated.

44. The herein described tube-finishing and polishing machine comprising in combination two sleeves arranged for rotation, a plurality of rolls arranged in a number of annular series, and formed to provide a gradually diminishing central opening, and means for imparting rotation to said sleeves.

45. The herein described tube-finishing machine comprising in combination two sleeves, a plurality of rolling rolls arranged in a number of annular series within the sleeves, and formed to provide a gradually diminishing central opening through the sleeves, and a plurality of elongated rolls at one end of the series of rolls forming the diminishing central opening.

46. The herein described tube-finishing and polishing machine, comprising in combination a sleeve mounted for rotation, a plurality of rings arranged therein and fixed to rotate therewith, an annular series of rolls arranged within each ring, a number of the annular series being of the same length, and some thereof being elongated, said annular series being formed to define an opening of varying size, as and for the purpose specified.

47. The herein described tube-finishing and polishing machine, comprising in combination a sleeve mounted for rotation, a plurality of rings arranged therein and fixed to rotate therewith, an annular series of rolls arranged within each ring, a number of the annular series being of the same length, and some thereof being elongated, said annular series being formed to define an opening of varying size, and means for forwarding a tube through said mechanism.

48. The herein described tube-finishing and polishing machine, comprising in combination a sleeve mounted for rotation, a plurality of rings arranged therein and fixed to rotate therewith, an annular series of rolls arranged within each ring, a number thereof of the annular series being of the same length, and some thereof being elongated, said annular series being formed to define an opening of varying size, means for forwarding a tube through said mechanism, and means for holding a tube against rotation in its passage therethrough.

49. In a device of the class described, two spaced elongated tube-forwarding mechanisms, in combination with a polishing and finishing machine interposed therebetween, and comprising a sleeve mounted for rotation, and a plurality of annular series of

small cylindrical rolls arranged within the sleeve and substantially defining a central opening therethrough.

50. In a device of the class described, two spaced elongated tube-forwarding mechanisms in combination with a polishing and finishing machine interposed therebetween, and comprising a sleeve mounted for rotation, a plurality of annular series of small cylindrical rolls arranged within the sleeve and substantially defining a central opening therethrough, and means for rotating said sleeve at high speed.

51. In a device of the class described two elongated tube-forwarding mechanisms arranged in spaced alignment, in combination with polishing mechanism interposed therebetween and comprising two sleeves mounted for rotation, a plurality of annular series of cylindrical rolling rolls arranged within each sleeve, and means for rotating each sleeve separately.

52. The herein described mechanism comprising in combination two spaced aligned tube-forwarding machines, and a tube-finishing and polishing machine interposed therebetween, and comprising a rotatable sleeve, and a number of annular series of rolling rolls arranged within the sleeve and formed substantially to define a central opening diminishing in size from one end to the other.

53. In a device of the class described, two aligned spaced tube forwarding machines, in combination with a tube-finishing and polishing mechanism, interposed therebetween, and comprising a sleeve mounted for rotation, a number of annular series of rolling rolls arranged within the sleeve, a number thereof formed to define a central opening diminishing in size from one end to the other, and an annular series of elongated rolling rolls arranged at one end thereof and formed to define a central opening of substantially the dimensions of the smallest of the openings defined by the other rolls, as and for the purpose specified.

54. In a machine of the class described the combination of two spaced tube-forwarding machines with an interposed polishing machine, the polishing machine comprising two sleeves mounted for rotation, a plurality of abutting rings arranged within each sleeve, each ring containing an annular series of rolling rolls, the rolls and rings being formed to define an opening diminishing in size gradually from one end to a short distance from the other end, a series of elongated rolls arranged to define an opening of substantially the same size as the smallest of the shorter rolls, and means for rotating the sleeves in opposite directions to equalize the torsional effect of the rolls upon the tube.

55. The herein described improvement in machines for polishing tubing comprising a

ring having a cylindrical inner periphery in combination with an annular series of cylindrical rolls within said ring and presenting an internal circumference greater than that of any single roll.

56. The herein described improvement in machines for polishing tubing without an internal support, comprising means for holding tubing against rotation while forwarding it, in combination with an internally cylindrical ring and means for rotating the same at high speed, a series of small rolls arranged within said ring as a race, abutments for said rolls at the ends of said ring, and said ring and contained rolls being positioned to receive the tubing from said holding and forwarding means.

57. The improvement herein described, comprising a drum open at its ends, mounted for rotation at high speed and containing a roll-race, in combination with a series of rolls in said race, and means axially confining said rolls in said race.

58. The improvement herein described, comprising a drum open at its ends, mounted for rotation at high speed and containing a roll-race and roll-end abutments, in combination with a number of rolls spaced apart in said race and presenting their ends to said abutments. 25

59. The improvement herein described, comprising a drum open at its ends, mounted for rotation at high speed and containing a roll-race and roll-end abutments, in combination with a number of rolls in said race 30 and presenting their ends to said abutments, and means axially spacing said rolls in said race. 35

In testimony whereof, I have hereunto set my hand, this 16th day of Sept., 1913, in the presence of two subscribing witnesses. 40

MARSHALL BURNS LLOYD.
